SWITCH

Robert K. Winning, Wauwatosa, Wis., assignor to
 Clum Manufacturing Company, Milwaukee,
 Wis., a corporation of Wisconsin

Application September 30, 1935, Serial No. 42,757

7 Claims. (Cl. 200—67)

This invention relates to improvements in switches.

The switch herein disclosed has a specialized function in connection with the preselective electro-vacuum gear shifter employed on certain current automobiles. More generally, however, the present switch performs the function of a reversing switch with a snap action and various of its features are usable on switches generally.

It is the primary object of the invention to provide a novel and improved switch construction, employing a snap action mechanism with lost motion between the actuator and the contact carrier sufficient to assure a substantially complete throw of the actuator before the contact carrier snaps to its new position. In this connection, it is a further purpose of the invention to provide a simple, inexpensive and effective type of snap action mechanism peculiarly adapted to be installed in extremely small and compact form between concentric oscillatory members.

It is a further very important object of the present invention to provide a novel and simplified form of self-equalizing bridge contacts of such a character that the compression of a single contact spring is divided between a number of different contacts on the contact carrier and is then divided between the ends of the respective contacts so that in all positions of the carrier the pressure exerted by the moving contacts upon the fixed contacts will be substantial at all points.

But for this arrangement, the moving contacts might engage selected fixed contacts and remain either wholly or partially out of engagement with other fixed contacts. Due to the novel and simple construction hereinafter to be disclosed, some portion of the pressure of the single compression spring is distributed to effect engagement of all contacts.

In the drawing:

Fig. 1 is a side elevation of the switch as it appears when installed in the mechanism for which it is specifically adapted.

Fig. 2 shows an interior view of the switch casing as it appears with the back removed and the moving contact carrier removed to expose the snap action mechanism.

Fig. 3 is a plan view of the moving contact carrier.

Fig. 4 is an inverted plan view of the fixed contact carrier or switch back.

Fig. 5 is a detail view of the switch in cross section.

Fig. 6 is an enlarged detail view of one of the equalizing bridge contacts as viewed on the line 6—6 of Fig. 3.

Fig. 7 is a front elevational view of the switch casing.

Fig. 8 is a view similar to Fig. 3 illustrating a modified form of contact carrier.

Fig. 9 is a plan view of a modified snap action mechanism.

Fig. 10 is an "exploded" view, showing in perspective the driving head and one of the associated spring guides.

Like parts are designated by the same reference characters throughout the several views.

The preselective electro-vacuum gear shifter in which this switch may find a specific use is described in the issue of the publication entitled "Automotive Industries" and dated December 15, 1934 (vol. 71, p. 732). The switch casing 10 is mounted by means of its flange 11 in a housing 12 which forms the cover of a diaphragm chamber 13. The diaphragm 14 carries a fitting at 15 connected by link 16 to the rocker arm 17 which is mounted on the squared end of the rock shaft 18. The case is embossed to provide semi-conical stops outwardly projecting at 19 to limit the movement of oscillation of the lever or rocker arm 17. Similar bosses inwardly projecting at 20 limit the range of oscillation of the contact actuator 25.

The contact actuator 25 oscillates coaxially with shaft 18 being preferably mounted loosely upon the shaft and held in place by the cylindrical head 26 fixed at the inner end of the shaft and provided with longitudinally extending oppositely disposed grooves at 27 for the spring guides of the snap action mechanism. The actuator 25 is in the form of a plate having arcuate upturned end portions at 28 shouldered to provide a seat for the contact carrier 29 and having lugs 30 projecting beyond its shoulders for engagement in the notches 31 of the contact carrier.

Each of the end flanges 28 is apertured to receive slidably the rod-like end of the guide 34 for a compression spring 35. Each of the guides 34 has a wide flat terminal portion 36 oppositely notched at 37 and pivotally engaged in one of the grooves 27 of the spool-shaped driver head 26 on the rock shaft. The shoulder provided by the terminal portion of each spring guide at 38 seats one end of the compression spring 35, the other being seated directly against the upturned flange 28 of the actuating plate 25.

The arrangement is such that the reaction of compression springs 35 in any given position of

rest of the parts tends to oscillate the rock shaft 18 in one direction by pressure of the heads 36 against the sides of the groove in the rock shaft head member 26. At the same time the compression of springs 35 is exerted in the opposite direction upon the upturned flanges 28 of the actuator to tend to oscillate the actuator oppositely to the rock shaft. The actuator and the rock shaft are thereby normally held by springs 35 at 10 the limit of their range of oscillation through engagement with the respective stops 20 and 19.

When the rock shaft is oscillated from its position of rest, it first subjects the springs 35 to additional compression and the arrangement 15 is such that not until the rock shaft approaches the extreme of its movement in the other direction does the snap mechanism cross dead center to reverse the thrust on the actuator 25, thereby causing such actuator to snap vigorously into 20 engagement with the opposite stop.

Preferably, though not necessarily, the driver head 26 is made spool-shaped, as shown in Figure 10, with flanges which, in the extreme positions 25 of the parts, enter the notches 37 in the terminal portions 36 of the respective spring guide rods 34 (see Figure 2). The flanges on the driver 26 extend the depth of the recesses 27 to guide the spring guide rods and firmly seat against the driver even in the extreme position illustrated 30 in Figure 2, the notches 37 affording sufficient clearance to permit of this increase in depth of the grooves 27.

To further insure against the release of the terminal portion of rods 34 from the grooves 27 35 of the driver heads 26 I may provide the contact actuator stem 25 with up-turned arcuate flanges at 39 behind the ends of which the terminal portions of the respective rods 34 engage in their extreme positions, as shown in Figure 2.

40 The moving contact carrier floats free of the shouldered portions of flanges 28 under the pressure of a single compression spring 40 which is seated in a socket in the head portion 26 of the rock shaft 18. Since the pressure of compression 45 spring 40 is centrally applied, and since the contact carrier is fully floating, it will automatically adjust itself to distribute the pressure of the spring to any three or less points of engagement. In the form of contact carrier shown in Figure 3, 50 there are only two contacts 42 and accordingly the pressure of the spring acting on the contact carrier is thereby divided between these two contacts. In the form of contact carrier shown at 29' in Fig. 8, there are three of the contacts 42 55 between which the pressure of the spring will be divided. Since three contacts will ordinarily serve to perform even the most complex switching operations, it will be obvious that for all ordinary purposes the spring pressure may be equally divided between the contacts.

Since the contacts disclosed are adapted to bridge two stationary contacts or terminals, it will further be apparent that if one of these terminals should be higher than the other, the 65 contact, if rigid, would be prevented from performance of its bridging function since its engagement with the high terminal would hold it free of engagement with the other.

Accordingly, in order further to divide the 70 pressure of the single spring, I have adapted the contacts 42 for individual pivotal movement about fulcrums intermediate their terminal portions. The construction clearly appears in Figs. 3, 6, and 8. These particular contacts are preferably in arcuate form and accordingly a strip

of metal of arcuate form has its ends turned down as shown at 43 to pass through openings 44 in the contact carrier 29, whereby the oscillation of the contacts 42 with the contact carrier is assured. These apertures 44 are sufficiently large so that they do not restrict the freedom of movement of the downwardly turned ends or prongs 43 of the contact 42. In order to provide a fulcrum upon which the contact may tilt to adjust itself for engagement with the fixed terminals or contacts, I preferably emboss downwardly each 5 opposite marginal portion of the strip comprising the contactor 42, thereby providing the fulcrum members 45 at opposite sides of the intermediate portion of the contactor, the intervening area along the center line of the contactor being unchanged. It will be apparent from Fig. 6 that each one of the contactors 42 is free to oscillate upon its laterally disposed integral fulcrum bosses at 45 so that the end portions of its generally planiform contact surface may accommodate themselves to the fixed terminals.

Fixed in the end of the switch barrel or casing 10 is the fixed contact carrier or terminal head 48. Like the contact carrier 29, the fixed contact carrier or terminal head 48 is made of dielectric material such as fiber or bakelite. The particular disposition of the fixed contacts or terminals therein will, or course, depend on the particular function for which the switch is made. In the present device, the contacts are arranged in sets of three as clearly shown in Fig. 4, the two supply contact rivets being designated by reference characters 49 and 50, respectively, and the output contact rivets being designated by reference characters 51, 52, 53, and 54. The contacts 51 and 52 are connected by a conductor 55 and the contacts 53 and 54 are connected by a conductor 56. It will be apparent that in one position of the contact carrier 29 its bridge contacts 42 will 40 respectively connect contacts 49 and 51 at one side and contacts 50 and 54 at the other side. In the other position of the contact carrier 29, its bridge contacts 42 will respectively connect terminal contacts 49 and 53 at one side and 45 52 and 50 at the other.

In the snap action mechanism shown in Fig. 9 the compression springs 35 instead of being seated at one end upon the flanges 28 of the contact actuator 25 are seated at both ends upon the shouldered portions of T-shaped guide members having their respective stems overlapping within the springs. Each of the T-shaped guide members 58 has a head, the head of one being engaged in the groove 27 of the rock shaft 26 and the head of the other being engaged in a similar fulcrum recess provided at 59 in the flanged end of the actuator 25. The compression spring 35 not only tends to elongate the combined length of the spring guides 58 but also confines their shank portions for relative sliding movement upon each other. The operation of the snap mechanism shown in Fig. 9 is exactly the same as that of the mechanism shown in Fig. 2. In either case an almost complete throw of the rock shaft occurs before the snap action functions to displace the contact actuator. In the particular preselective gear shifting device in which this switch is used, this organization makes it impossible for the contact actuator to function prematurely and the arrangement insures that the remaining mechanism to which the diaphragm 14 is connected will be in proper position before the switch operates.

It will further be apparent that each end of each of the bridge contactors 42 on the carrier

29 must be in pressure engagement with the fixed contact rivet over which it lies. The pressure of the single compression spring 40 which acts on the carrier 29 is first divided between the several bridge contacts 42 and then, by the oscillation of these contacts upon their respective fulcrums, the portion of spring thrust allotted to each contact is divided between the ends thereof to insure operative engagement with the terminal. This feature makes it unnecessary to support the ends of the several contacts with individual springs and the construction and operation of the switch is thereby greatly improved and rendered economical. The contacts 42, as shown in detail in Fig. 6, may be made up independently of other portions of the switch mechanism for incorporation in this or other switches.

I claim:

1. In a switch, a rotatable disk comprising a contact carrier provided at intervals about its periphery with substantially radial notches, and a balanced series of contact elements on the face of said disk, each element having fulcrum means intermediate its ends and each element providing two contact surfaces and tongues engaged through said notches, the several elements being arcuate about the axis of said disk for pivotal movement upon substantially radial fulcrum axes.

2. In a switch, a substantially rigid contact comprising a strip of metal having a substantially planiform contact surface interrupted only adjacent the margins of the strip by integrally formed marginal fulcrum bosses.

3. In a switch, a substantially rigid contact comprising a strip of metal having a substantially planiform contact surface interrupted only adjacent the margins of the strip by integrally formed marginal fulcrum bosses, the ends of said strip being bent substantially at right angles to said contact surface to comprise guiding tongues.

4. In a switch, the combination with a contact carrier of insulating material provided with a face portion having openings, of a contact element comprising a strip provided with fulcrum means intermediate its ends, contact surfaces at

each side of said fulcrum means, and at least one tongue projecting from an end of said strip into an opening of said surface to position said strip while accommodating its pivotal movement upon said fulcrum means.

5. The combination with a contact element comprising an arcuate strip provided intermediate its ends with marginally disposed fulcrum means, said strip having contact surfaces at each side of said fulcrum means and being provided therebeyond with integral tongues formed substantially at right angles to said strip, of a contact carrier having means engaged loosely by said tongues to position the contact element upon the face of the carrier while permitting the rocking movement of the contact strip upon said fulcrum means.

6. In a switch, the combination with a contactor comprising a contact actuator, a contact carrier and contact means mounted on said carrier, of a driver mounted co-axially with said actuator, stops limiting the movement of said driver and said actuator between predetermined respective positions, the driver having a peripheral notch, a spring guide having a terminal portion seated in said notch and another portion engaging the contact actuator of said contactor, and compression spring means carried by said guide and exerting its pressure oppositely upon said actuator and the notched peripheral portion of said driver.

7. In a switch, the combination with a socketed driver mounted for oscillation, of a co-axially oscillatable contact actuator, a contact carrier connected for oscillation with said actuator, a spring seated in the socket of said driver and bearing on said carrier, contact means mounted on said carrier, a terminal head providing complementary contact means with which the contact means of the carrier is cooperative, and snap action mechanism operatively connecting said driver with said actuator for the delayed snapping operation of the actuator upon the completion of a predetermined movement of the driver.

ROBERT K. WINNING.
